UNITED STATES PATENT OFFICE.

ALFRED COTTON, OF ST. LOUIS, MISSOURI, ASSIGNOR TO HEINE SAFETY BOILER COMPANY, OF ST. LOUIS, MISSOURI, A CORPORATION OF MISSOURI.

STACK-DAMPER.

1,395,395.

Specification of Letters Patent.

Patented Nov. 1, 1921.

Application filed December 10, 1919. Serial No. 343,703.

To all whom it may concern:

Be it known that I, ALFRED COTTON, a citizen of the United States, residing at St. Louis, Missouri, have invented a certain 5 new and useful Improvement in Stack-Dampers, of which the following is a full, clear, and exact description, such as will enable others skilled in the art to which it appertains to make and use the same.

10 This invention relates to dampers of the kind that are used for cutting off communication between a flue, stack or chimney and a chamber or passageway from which or through which gases escape into said flue 15 when the damper is open.

The main object of the invention is to provide an efficient damper for flues, stacks or chimneys that is of simple design, easy to operate and inexpensive to manufacture and 20 install.

Another object is to provide a practicable damper for use in apparatus of the kind wherein waste heat is used to operate a boiler, that is compact and of such design 25 that it is not liable to become inoperative through warping or lack of frequent use. Other objects and desirable features of my invention will be hereinafter pointed out.

I have herein illustrated my invention 30 embodied in a damper that is used for normally cutting off communication between a stack and a gas passageway or chamber that is connected up with a boiler in such a manner that the boiler can be heated by 35 waste gases from said passageway, said damper being adapted to be opened when the boiler is cut out of service, so as to cause the waste gases to pass from said passageway or chamber into the stack which the 40 damper controls. I wish it to be understood, however, that my invention is not limited to a damper for use in an apparatus of the particular kind shown or to a damper of the particular construction and arrangement 45 herein described.

Figure 1 of the drawings is a horizontal sectional view of an apparatus provided with a square chimney or stack equipped with a damper constructed in accordance 50 with my invention.

Fig. 2 is a side sectional view of said apparatus, the main stack being shown in vertical section.

Fig. 3 is a vertical transverse sectional view, taken on the line 3—3 of Fig. 2, looking in the direction indicated by the arrow. 55

Figs. 4 and 5 are detail perspective views illustrating removable elements such as are used in my improved damper.

Fig. 6 is a horizontal sectional view, illustrating my improved damper used in connection with a circular chimney or stack. 60

Fig. 7 is a vertical longitudinal sectional view, taken on the line 7—7 of Fig. 6, looking in the direction indicated by the arrows; and 65

Fig. 8 is a vertical transverse sectional view, taken on the line 8—8 of Fig. 6.

Referring to Figs. 1 to 3 of the drawings which illustrate my invention applied to a 70 square chimney or stack, A designates a gas chamber herein illustrated as a cement kiln, B designates a boiler that is adapted to be operated by the waste gases from the chamber or kiln A, C designates a vertically-disposed stack through which the gases from the chamber A escape when the boiler B is not in service, D designates a fan or other suitable suction device for causing the waste gases from the chamber A to circulate over the heating surface of the boiler B and E designates the stack from which the gases escape from the boiler. The kiln A is normally cut off from the stack C by 75 means of a damper F that can be constructed and arranged in various ways without departing from the spirit of my invention. In the apparatus illustrated in Figs. 1 to 3 the chamber A discharges into a transverse flue or passageway G that is connected with the boiler B by means of a flue H. The stack C is arranged at one side of the point where the chamber A and flue H connect with the transverse flue G and said transverse flue connects with the stack C at 80 the lower end of same below the damper F, as indicated by the reference character 1 in Fig. 3. Under normal conditions, or, in other words, when the damper F is closed, the fan D draws the waste gases from the chamber A at a high speed through the boiler B, thus producing a slight vacuum at 85 the exit of the chamber or kiln A. If it is desired to cut the boiler B out of service, or if the boiler becomes disabled, the damper F 90

is opened so as to cause the waste gases from 95 the chamber A to pass through the damper F into the stack C. The damper F is arranged to be closed when the fan D is not in operation, so that the waste gases from the chamber A will not be drawn through the damper F into the stack C. 100

105

the kiln A to enter the transverse flue G, then dive downwardly to the inlet 1 at the lower end of the stack C and thence upwardly through said stack, the gases taking 5 this path on account of the suction that the stack C exerts on the transverse flue or passageway G into which the kiln discharges.

A practical damper for the purpose mentioned, namely, a damper that is intended to 10 be opened only at infrequent intervals, must be of such design that it is not liable to become inoperative through neglect, warping, accumulation of dust or lack of frequent use, and when used in an apparatus that has been 15 changed or modified by adding a boiler to utilize the waste heat from the apparatus, it must be compact, inexpensive to manufacture and install and easy to operate. The damper F which constitutes the invention 20 herein described has all of the desirable features just pointed out and in its simplest form is composed of a number of members 2 of cylindrical form that are adapted to be slid endwise into the stack C through an 25 opening 3 at one side of same onto a supporting means and then rolled sidewise or laterally from the center of the stack, as shown in Fig. 1, said elements 2 extending parallel to each other and coöperating with 30 each other to form a horizontally-disposed partition in the stack C. If desired, the closure formed by the members 2 can be rendered more effective by spreading a layer of sand or ashes over said members 2, as 35 indicated by the reference character 4 in Figs. 1, 2 and 3. The means that supports the removable damper elements 2 can be formed in various ways, but I prefer to arrange horizontal ledges 5 on the inside of 40 the stack at the front and rear sides of same with their upper edges flush with a supporting arch 6, as shown in Fig. 2, said ledges serving as supports for the ends of the removable damper elements 2. The damper 45 elements 2 may consist of cylindrical shaped members formed of fire clay or other suitable refractory material, as shown in Fig. 5, and in some cases it is practicable to use pieces of metal pipe, such as old boiler 50 tubes, as shown in Fig. 4, to form the damper F; for example, in cement plants where there is enough vacuum below the damper F to insure sufficient air leaking downwardly between the damper elements to keep them 55 cool. Each of the damper elements may be provided with a ring or other suitable device 2^a, as shown in Fig. 4, or 2^b, as shown in Fig. 5, arranged at one or both ends of same in which the end of a hooked rod can 60 be inserted to facilitate withdrawal of the damper elements, said damper elements being adapted to be rolled toward the center of the stack and then slid endwise along the supporting arch 6 out of the opening 3 in 65 the stack when it is desired to open the dam-

per. In urgent cases the damper elements 2 may be drawn sufficiently toward the opening 3 in the stack to allow them to drop off the supporting ledges down into the bottom of the stack. In Figs. 6, 7 and 8 of the 70 drawings I have illustrated my invention applied to a round chimney or stack. The stack C is provided on its interior with front and rear ledges 5 on which the end portions of the damper elements 2 rest and 75 a supporting arch 6 arranged in alinement with the opening 3 in the front side of the stack through which the damper elements are introduced. Horizontally - disposed ledges 5^a are arranged at the sides of the 80 stack, as shown in Figs. 6 and 7, so as to fill the spaces between the end damper elements 2 and the adjacent portions of the side wall of the stack and the top faces of said side ledges 5^a are preferably made a trifle higher 85 than the top faces of the ledges 5 on which the end portions of the damper elements rest, so as to form stops against which the end damper elements strike when they are moved laterally into operative position. If 90 desired, the rear ledge 5, on which the rear end portions of the damper elements rest can also be provided with a raised portion, as shown in Fig. 8, so as to form a stop 95 against which the rear ends of the damper elements strike when they are introduced into the stack, thereby preventing the damper elements from being pushed inwardly so far that the front ends of same will not 100 rest properly on the front ledge 5 when said damper elements are rolled laterally into operative position.

Having thus described my invention, what I claim as new and desire to secure by Letters Patent, is:

1. A vertically-disposed stack or flue having a side opening therein, a supporting structure arranged on the inside of said stack, and a plurality of cylindrical-shaped damper elements that are adapted to be introduced endwise into said stack through the opening therein and then rolled laterally into operative position on said supporting structure. 110
2. A vertically-disposed stack or flue having a side opening therein, ledges arranged on the inside of said stack, and a plurality of cylindrical shaped damper elements that are adapted to be introduced endwise into said stack through the opening therein and then rolled laterally into operative position on said ledges. 115
3. A vertical stack or flue provided with an opening, a supporting arch in said stack and arranged in proximity to said opening, ledges in the stack arranged at substantially right angles to said supporting arch, and a plurality of cylindrical-shaped-damper elements that are adapted to be introduced endwise into said stack on said supporting 125 ledges. 130

arch and then rolled laterally on said ledges so as to form a removable partition in the stack.

4. A vertical stack or flue provided with an opening, ledges arranged inside of said stack in proximity to said opening, cylindrical shaped damper elements arranged in said

stack in parallel relation to each other with their ends supported on said ledges, and side ledges on the inside of the stack extending parallel with said damper elements and projecting higher than the ledges on which the ends of the damper elements rest. 10

ALFRED COTTON.
